METHOD AND APPARATUS FOR THE MANUFACTURE OF A SPIRAL

Walter J. Podbieliak, Chicago, Ill.

Application June 25, 1936, Serial No. 87,221

13 Claims. (Cl. 153—64)

This invention relates to a method and apparatus for the manufacture of a spiral sheet having a spiral passageway and more particularly to a spiral sheet for use in a rotor through which fluids are caused to travel counter-currently in the spiral passageway due to centrifugal force set up by the rapid rotation of the rotor.

In my prior application directed to the art of Securing contact between fluids, Serial No. 5,059, filed February 5, 1935 patented September 21, 1937, No. 2,093,645; and in my copending application to a Centrifugal fluid-treating apparatus, Serial No. 87,224, filed June 25, 1936, I have disclosed apparatus embodying rotors through which fluids of different densities are caused to travel counter-currently. These rotors are provided with spirally wound sheets to form a spiral passageway through which the fluids pass counter-currently in continuous uninterrupted streams.

In accordance with my invention I provide a novel apparatus and method for constructing these spiral sheets which is simple in design and construction and which is capable of ready manipulation to carry out the steps of the process.

The apparatus embodying my invention is designed to form a sheet of any desirable material, suitably metallic in nature, into a spiral and to retain the spiral windings of the sheet at a predetermined pitch. The spiral sheet while so retained is then treated in a novel manner which permits the removal of the spirally wound sheet in its set form from the apparatus and assures its retention in that form until it is placed in the rotor casing and affixed therein in the desired position. This is accomplished by filling the spiral passageway of the spirally wound sheet while it is retained in the aforementioned apparatus, with a liquefied thermo-plastic material such as wax and then permitting the wax to harden. The hardened or set wax serves to maintain the desired relationship of the windings of the spiral and can be readily removed from the spiral after it is installed in the rotor.

The apparatus employed by me and the process for making the spiral will be readily understood from the following description taken in conjunction with the accompanying drawings, which form a part of my specification and in which:

Figure 1 is a plan view with parts removed and broken away of an apparatus embodying my invention in which a metal sheet has been wound into a spiral of the desired pitch;

Fig. 2 is a transverse sectional view thereof taken along the line 2—2 of Fig. 1;

Fig. 3 is a transverse sectional view thereof taken along the line 3—3 of Fig. 1, shown with parts telescoped; and

Fig. 4 is an enlarged fragmentary detail view, with parts in section, of a novel engaging device utilized in an apparatus embodying my invention.

Referring more particularly to Figs. 1 to 3 of the drawings, I have shown a spirally wound sheet 10 of predetermined pitch retained in its wound form by a retention apparatus and having the connecting spaces between the successive turns 11 of the spiral filled with a suitable thermoplastic material 12.

The retention apparatus comprises an upper 15 clamping plate or spider 13, and a lower spaced groove plate 14. The opposed faces of spider 13 and groove plate 14 may be suitably provided with centrally located opposed recesses 15 and 16 respectively into which the ends of a tubular 20 spacer 17 is retained. The spacer 17 serves to maintain a substantially fixed spaced relationship between the spider 13 and the groove plate 14 and its length may be varied as the width of the sheet to be spirally wound varies. The spider 25 13, the groove plate 14 and the tubular spacer 17 are assembled and retained in a unitary structure as by a central assembly bolt 18 having a screw-threaded tightening nut 19 at one extremity thereof.

From an inspection of Figs. 2 and 4 it is apparent that the lower edges of the spirally wound sheet 10 are retained in a spiral groove 20 formed in the upper face of the plate 14 and the upper edges of the sheet are rigidly engaged as by 35 slotted pins 21, forming part of an engaging device 22, which pass through the legs 27 of spider 13 to engage these free edges.

As stated above, the lower groove plate 14 is provided with a spiral groove 20. This groove 40 is formed in a spiral having a predetermined pitch between the successive turns of the groove and may be preferably so designed that it will at least temporarily retain the wound sheet 10 in its spiral form independently of other retention 45 means.

To accomplish this, groove 20 is formed with a substantially V-shape in which the bottom 23 is preferably flat and has a width less than the width of the mouth. As is readily apparent from 50 Fig. 2, the walls 24 and 25 of the groove slope away from the axis of rotation. The outer wall 25 of the groove, makes an angle of substantially 10° more or less, with a line drawn parallel to the axis of plate 14. Consequently, the outer wall 55 25

of the groove and the adjacent face of the plate meet or interact to form a sharp edge or corner 26. As the sheet 10 is urged into the groove 20 in the process of forming the spiral, the edge of 5 the sheet first contacts the inner wall 24 of the groove; and as the pressure is continued, the lower edge is urged to the bottom 23 thereof. The sheet is thus wedged against the corner 26 and is retained thereby. The bottom 23 of the groove 10 may suitably have a radial width which is either the same or preferably slightly less than the thickness of the sheet 10 so that the sheet may be 15 additionally retained by the frictional contact with the walls of the groove. The sheet 10 is thus capable of at least temporary retention in the spiral groove 20 of the plate 14. In the operation of my process successive portions of the lower edge of the sheet are retained temporarily by the grooves until successive points of the 20 upper edge are grasped by the slotted pins 31 of the engaging device 22 in a manner to be described.

The spider 13 comprises a central hub through which the tightening bolt 18 passes and in the 25 under-face of which the recess 15 is formed. Diametrically opposed legs or extensions 27 may suitably be formed integral with the hub and are provided with apertures or perforations, having the upper portions threaded, through 30 which the slotted pins 21 of the engaging device 22 are passed to engage the upper edge of the sheet 10 as is clearly shown in Fig. 4. To form the spider 13, I may suitably provide a plate in which the under-face is formed with a spiral 35 groove 36 (Fig. 3) coinciding in pitch to the groove 20 in the groove plate 14. Segmental portions 28 are cut out from this plate to form the hub and diametrically opposed legs 27 of the spider. The perforations in the legs 28 are formed 40 in spaced intervals and their axes intersect the grooves on the underface thereof. Hence the perforations, and consequently the engaging devices 22 positioned therein, are so arranged on the legs 27 of the spider that an imaginary spiral 45 line of predetermined pitch will pass through the centers thereof. Thus, the arrangement of the engaging devices 22 is such as to define a spiral line of a pitch coinciding with the pitch of the groove 20 in the plate 14. The segmental portions 28 are retained for use in the process of 50 manufacturing the spiral sheet for a purpose to be hereinafter described.

The engaging devices 22 (Fig. 4) comprise an upper threaded stud or bolt 29 and a lower slotted 55 pin 21. Any suitable means may be employed to connect the bolt 29 and pin 21 so that the bolt will push or pull the pin through the perforations without imparting any turning or twisting movement thereto. In the drawings, I show one means 60 for accomplishing this desired movement as for example a ball 30 formed integral with the pin 21 and a socket 31 formed integral with the bolt 29 to form a ball and socket joint; however, any other suitable means, obvious to one skilled in the 65 art, may be employed to accomplish the desired movement of the pin.

The spiral sheet 10 may be secured in the retention apparatus in the following manner.

The sheet to be wound into a spiral may be 70 formed of any substantially rigid and flexible material such as metal, artificial condensation products of the phenol-formaldehyde or polyhydric alcohol-dibasic acid types such as "Bakelite" or "Glyptal", or like materials. Preferably, however, 75 I utilize a sheet made from some suitable metal

such as spring tempered steel, stainless steel, or Monel metal preformed into a spiral sheet with a pitch between the successive turns of the sheet larger than the pitch of the groove in the plate 14. The preformed spiral sheet is placed on the 5 groove plate 14 with one edge, designated as the lower edge, opposed to the groove 20 and the spider is supported on the tubular spacer 17. The assembly is retained in place by the bolt 18 and nut 19. One portion of the lower edge of the 10 spiral sheet is sprung into the groove 20 and the opposed portion of the upper edge is engaged as by the slotted pin 21 urged through the perforation in the overlying leg as by the bolt 29. Successive portions of the lower edge of the spiral 15 sheet are sprung into the groove and the corresponding successive opposed edges are engaged by the slotted pins 21 urged through the succeeding legs. This operation is continued until the sheet has been formed into a spiral of the desired pitch 20 and size. As set forth above, the engaging devices 22 pass through the apertures in the legs 27 along a spiral imaginary line of predetermined pitch and accordingly the engaging devices are set as closely as possible along this line in order to provide 25 sufficient retention for maintaining the sheet in its desired spirally wound form while the thermoplastic material is poured into the spiral passageway.

The assembled device is now formed into a 30 relatively rigid structure as by the tightening of the nut 19 and the bolts 29 of the engaging device 22. In order to properly position the spider 13 and the groove plate 14 so that the pins 21 of the engaging device 22 define a spiral line 35 that coincides with the groove 20, I may provide suitable centering means as for example lugs or extensions 33 and corresponding recesses 34 in the spider 13 and plate 14 respectively.

The assembled relatively rigid spiral sheet is 40 now ready to receive the thermoplastic material. The thermoplastic material, in liquefied form, may be poured directly into the spiral passageway between the successive turns 11 of the sheet 10; however, I prefer to employ an additional 45 precautionary measure to assure the maintenance of the desired pitch of the spiral while the thermoplastic material is being poured and while it sets. For this purpose, I make use of the segments 28 cut from the spider sheet as heretofore 50 described. These segments have grooves 36 in the under-face which coincide in size, shape and pitch with groove 20. The grooves 36 of the segments 28 are now pressed onto the top edges of the spirally wound sheet 10 lying between the 55 legs 27 of the spider 13, Fig. 3. It is obvious that the individual segments 28 must be positioned in the same position in relation to the legs 27 that they occupied before the legs 27 were formed, so that the underlying groove 36 will coincide 60 with the groove 20 in plate 14. Each of the segments may be provided with suitable openings 35 through which the molten thermoplastic material may be poured to fill the spiral passageway between the successive turns of sheet 11, although 65 this is not necessary as the thermoplastic may be poured through a single opening in only one of the segments.

When the thermoplastic material has set, the retention apparatus can be safely removed in 70 an obvious manner and the spiral placed and assembled in the rotor in which it is to be used. The thermoplastic can be then removed from the spiral passageway in any desirable manner 75 as by heat or suitable solvent for the thermo-

plastic material. Although I have set forth above that wax is the thermoplastic material I employ, it is obvious that any other suitable and well-known thermoplastic material, having sufficient adhesiveness when set, can be used. For example, any of the well-known plastic rubber isomers or cellulose derivatives can be used in lieu of the wax.

While Figs. 1-4 show two sheets wound in spiral form, I have described only one sheet together with the process of winding and forming it and the apparatus required to perform such process. It is obvious that the operations with respect to the second sheet are duplications of those described in connection with the first sheet. By means of my process and apparatus I can suitably form sheets up to 300 feet or more in length into spirals having the desired pitch and with clearance between the successive turns say from $\frac{1}{2}''$ to $\frac{1}{4}''$. Obviously, the clearance differences between the successive turns may be decreased below $\frac{1}{2}''$ and increased above $\frac{1}{4}''$ to suit the desired needs.

Although I have shown sheet 10 as formed into a spiral of constant pitch, it is to be understood that I consider it within the purview of my invention to utilize my apparatus and carry out my process for forming spirally wound sheets of varying pitch. Furthermore, my invention is not to be construed as limited to a spider embodying the use of four legs, as shown in the drawings, as it is obvious that the number of the legs in the spider may be varied to suit the desired need, thus a smaller or larger number of legs may be employed with like results. If the number of legs be increased, say to six or more, then the use of the cut-out segments may be advantageously dispensed with.

The above modifications and others obvious from the drawings and description are included within the scope of my invention and my invention is not to be construed as limited to the described process and form shown except as such limitations appear in the claims. My process comprehends the formation of a spiral in which a sheet may be engaged at a point and the sheet turned about the engaged point and alternatively wherein the engaged point is turned about an axis to wind the sheet into a spiral.

I claim:

1. In the manufacture of a spiral sheet from a flat substantially rectangular sheet to form a passageway between the successive turns of the sheet comprising, engaging a longitudinal edge of the sheet at a point near the end thereof, winding the sheet about said secured point, engaging successive points along said edge, said points being so arranged that a spiralling line, of predetermined pitch, will pass through the points, simultaneously engaging the other longitudinal edge of the spirally wound sheet in a spiral groove having a pitch substantially the same as the pitch of the turns of the sheet at the secured edge and substantially filling the passageway of the spiral with a thermoplastic material.

2. In the manufacture of a spiral sheet from a flat substantially rectangular sheet to form a passageway between the successive turns of the sheet comprising, guiding a longitudinal edge of the sheet in a spiral groove having a predetermined pitch and engaging successive points along the other longitudinal edge, said points being so arranged that a spiral line, having substantially the same pitch as the pitch of the groove, will pass through the points.

3. In the manufacture of a spiral sheet from a flat substantially rectangular sheet to form a passageway between the successive turns of the sheet comprising, guiding a longitudinal edge of the sheet in a spiral groove having a predetermined pitch, engaging successive points along the other longitudinal edge, said points being so arranged that a spiral line, having substantially the same pitch as the pitch of the groove, will pass through the points and substantially filling the passageway between the successive turns of the sheet with a thermoplastic material.

4. In the manufacture of a spiral sheet from a flat substantially rectangular sheet to form a passageway between the successive turns of the sheet comprising, guiding a longitudinal edge of the sheet in a spiral groove having a predetermined pitch and simultaneously engaging successive points along the other longitudinal edge, said points being so arranged that a spiral line, having substantially the same pitch as the pitch of the groove, will pass through the points.

5. In the manufacture of a spiral sheet from a flat substantially rectangular sheet to form a passageway between the successive turns of the sheet comprising, guiding a longitudinal edge of the sheet in a spiral groove having a predetermined pitch, simultaneously engaging successive points along the other longitudinal edge, said points being so arranged that a spiral line, having substantially the same pitch as the pitch of the groove, will pass through the points and substantially filling the passageway between the successive turns of the sheet with a thermoplastic material.

6. In an apparatus for the manufacture of a spiral sheet having a passageway of predetermined pitch between the successive turns of the sheet, a spider having perforations formed therein along a spiral line of predetermined pitch and engaging means removably retained in said perforations.

7. In an apparatus for the manufacture of a spiral sheet having a passageway of predetermined pitch between the successive turns of the sheet, a spider having perforations formed therein along a spiral line of predetermined pitch and engaging means removably retained in said perforations, said engaging means comprising a slotted pin.

8. In an apparatus for the manufacture of a spiral sheet having a passageway of predetermined pitch between the successive turns of the sheet, a spider having perforations formed therein along a spiral line of predetermined pitch and slotted pins removably retained in said perforations.

9. In an apparatus for the manufacture of a spiral sheet having a passageway of predetermined pitch between the successive turns of the sheet, a spider having perforations formed therein along a spiral line of predetermined pitch, engaging means removably retained in said perforations, said engaging means being adapted to engage one edge of the spiral sheet, and a plate having a spiral groove therein of predetermined pitch, in which the other edge of the spiral sheet can be inserted.

10. In an apparatus for the manufacture of a spiral sheet having a passageway of predetermined pitch between the successive turns of the sheet, a spider having perforations formed therein along a spiral line of predetermined pitch, en-

gaging means removably retained in said perforations, and engaging means being adapted to engage one edge of the spiral sheet, and a plate having a spiral groove therein of predetermined pitch, in which the other edge of the spiral sheet can be inserted, said spiral groove being defined by walls which slope away from the axis of the spiral sheet.

11. In an apparatus for the manufacture of a spiral sheet having a passageway of predetermined pitch between the successive turns of the sheet comprising, a rigid plate member, a spiral groove of predetermined pitch in one face of the plate member, said spiral groove being defined by walls which slope away from the axis of the spiral sheet.

12. In an apparatus for the manufacture of a spiral sheet having a passageway of a predetermined pitch between the successive turns of the sheet comprising a rigid plate member, a spiral groove of predetermined pitch in one face of the plate member, said spiral groove being defined by walls which slope away from the axis of the spiral sheet.

spiral sheet, the wall of the groove adjacent the axis of the spiral sheet having a greater inclination than the other wall of the groove and the mouth of the groove having a greater axial width than the bottom thereof.

13. In an apparatus for the manufacture of a spiral sheet having a passageway of predetermined pitch between the successive turns of the sheet, a spider having legs radiating outwardly from a central hub, said legs having perforations formed therein along a spiral line of predetermined pitch, adjustable engaging means in said openings extending through the legs, a spaced plate having a spiral groove of predetermined pitch opposed to said spider, said groove being defined by walls which slope away from the axis of the spiral sheet, the wall of the groove adjacent the axis of the spiral sheet having a greater inclination than the other wall of the groove and the mouth of the groove greater axial width than the bottom thereof.

WALTER J. PODBIELNIAK.
